INVENTOR

DES. 2194

Louis Rebisse, of Buffalo, N.Y.

Letters Patent No. 2194 Dated Oct. 10-1865.

Design for a Bust of General Grant.

The schedule referred to in these Letters Patent and making part of the same.

To all whom it may concern:

Be it known that I, Louis Rebisse, now of the City of Buffalo, County of Erie and State of New York, have invented or produced a new and original design for a Bust of Gen. U. S. Grant, of which the following is a full, clear and exact description, reference being had to the accompanying photographic drawings making a part of this specification, in which Fig. 1 is a front view, and Fig. 2, a side view.

The position of the head is that which would naturally be assumed by the person when looking at an object directly in front.

The hair is represented as being cut short and parted on the left side the beard unshaven and trimmed close the lips compressed, expressing firmness and determination.

The drapery is a military dress coat and vest, rather low collar exposing the neck. Shoulder straps on coat, neck tie double bow in front.

What I claim as my invention and desire to secure by Letters Patent is the design for a Bust of Gen. U. S. Grant herein set forth.

Witnesses:

W. H. Forbush
J. H. B. H. Muckle

Louis Rebisse.
